UNITED STATES PATENT OFFICE.

EDWARD B. VANDERGAW, OF BROOKLYN, NEW YORK.

DESIGN FOR A PRINTED TEXTILE FABRIC.

No. 37,596.

Specification for Design.

Patented Oct. 24, 1905.

Application filed September 7, 1905. Serial No. 277,452. Term of patent 7 years.

To all whom it may concern:

Be it known that I, EDWARD B. VANDERGAW, a citizen of the United States, residing at Brooklyn, in the county of Kings and State of New York, have invented a new, original, and ornamental Design for Printed Textile Fabrics, of which the following is a specification, reference being had to the accompanying drawing, forming part hereof.

The figure is a plan view of the fabric, showing my new design.

I claim—

The ornamental design for a printed textile fabric as shown.

EDWARD B. VANDERGAW.
